COMBINATION DESK THERMOMETER AND MIRROR

Wallace A. Monson, St. Paul, Minn., assignor to Brown & Bigelow, St. Paul, Minn.

Application July 22, 1957, Serial No. 47,029

Term of patent 14 years

(Cl. D52—7)

Fig. 1

Fig. 2

Fig. 3

Fig. 4

Fig. 5

Fig. 6

Figure 1 is a front perspective view of a combination desk thermometer and mirror, showing my new design; Figure 2 is a rear perspective view thereof;

Figure 3 is a front perspective view with the mirror face exposed;

Figure 4 is an end elevational view of the combination, positioned for use as a thermometer;

Figure 5 is an end elevational view of the combination, positioned for use as a mirror; and

Figure 6 is a top plan view of the combination when used as a desk thermometer.

The dominant features of the design reside in the portions shown in full lines.

I claim:

The ornamental design for a combination desk thermometer and mirror, as shown and described.
